W. H. H. STINEMAN.

STOKER.

APPLICATION FILED DEC. 14, 1909.

970,660.

Patented Sept. 20, 1910.

UNITED STATES PATENT OFFICE.

WILLIAM H. H. STINEMAN, OF BALTIMORE, MARYLAND, ASSIGNOR OF ONE-HALF TO
ROBERT A. TAYLOR, OF BALTIMORE, MARYLAND.

STOKER.

970,660.

Specification of Letters Patent. Patented Sept. 20, 1910.

Application filed December 14, 1909. Serial No. 533,000.

To all whom it may concern:

Be it known that I, WILLIAM H. H. STINEMAN, a citizen of the United States, residing at Baltimore, in the State of Maryland, have invented certain new and useful Improvements in Stokers, of which the following is a specification.

My invention relates to improvements in furnaces and especially to that class in which the coal or other fuel is fed from the bottom of the furnace to the under side of the fire. In this class of devices the greatest efficiency and extent of fire surface are obtained, by providing a graduated fuel conveyer, by means of which a portion of the fuel will be forced out of said conveyer throughout its entire length, so that an equal distribution of the fuel to the fire will be accomplished. By graduating the feed device along the length of the fire box in the direction of the feed, the fuel will be distributed and deposited along the length of the fire box under the fire in even quantities to maintain a uniform supply throughout the area thereof.

The main object of my invention is to provide a graduated conveyer to reduce the carrying capacity thereof toward the rear of the fire-box, whereby a uniform distribution of the fuel in the fire-box will be maintained.

Another object is to provide an improved conveyer so constructed as to permit of natural draft throughout the fire box.

Another object is to provide a conveyer so constructed and arranged in the fire box as to permit of the fuel, or ashes, being removed from the fire box by simply reversing the rotation of the conveyer.

A further object of my invention is to provide means for manually operating the conveyer, when the fire is first started, until sufficient steam is generated to operate the conveyer by power.

My invention consists of the novel construction and arrangement of the parts and combination of parts hereinafter more fully set forth in the following specification and pointed out in detail in the claims.

In the accompanying drawings,—Figure 1 is a sectional view of the fire box, showing parts broken away. Fig. 2 is a plan view of Fig. 1, the hopper being in section.

Referring to the accompanying drawings,

forming part of this specification, and in 55 which like reference numerals designate like parts throughout the several views thereof, 1 designates a trough supported in the front and rear walls of the furnace and inclining upwardly at its rear end to conform to the 60 cone shape of the conveyer 2. The said cone-shaped conveyer 2 is hollow and open at each end and has its rear end journaled in the bearing 3, and its front end journaled in the front of the hopper 7. The shaft 5 of the conveyer is hollow and provided throughout its entire length with a number of apertures which register with the apertures 6 in the conveyer. The ends of the 65 hollow shaft 5 being open a natural draft 70 will be created therethrough, the same being evenly distributed in the fire box through the apertures 6. The air circulating through the shaft 5 and apertures 6 prevents the conveyer from becoming heated to too great 75 an extent, and also insure a more perfect combustion and assist in coking the fuel.

At the front of the trough 1 is arranged a hopper 7 communicating therewith, and having a neck 8 into which the front end 80 of the conveyer extends, the said hopper being slightly tapered or flared at its mouth. The conveyer 2 is cone shaped or tapered from a point adjacent the front wall of the furnace to the rear end, thus reducing its 85 carrying capacity toward the rear of the fire box which will cause the fuel to be forced over the sides of the trough 1 as it is carried along the said trough, thereby producing a uniform distribution of the fuel 90 over the grate 20 throughout the entire length of the fire box. The fire resting on the top of the conveyer will keep the trough 1 constantly filled and cause the conveyer to feed the fuel up over both sides of the 95 trough uniformly throughout its entire length.

In the bottom of the neck 8 of the hopper, is a door 9 hinged to the furnace and held up in its normal by a spring catch 10. This 100 door 9 may be opened to remove any hard or lumpy object from the hopper, or, when it is desired to draw the fire, or fuel, from the fire box, the fire or fuel being drawn from the fire box by simply reversing the 105 rotation of the conveyer.

On the front end of the shaft 5 is a gear wheel 11 which meshes with the worm 12 on

the power shaft 13. This shaft 13 is driven by means of power transmitted to the pulley 14. On the opposite end of the shaft 13 I have provided a crank 15 by means of which 5 the said shaft 13 may be operated when the fire is started and until sufficient steam is generated to drive said shaft by power.

A plunger 16 has its rear end pivoted to a lug 17 on the side of the hopper, and its 10 front end projecting through an opening 18 in the neck of the hopper. A link 19 connects the said plunger with the gear wheel 11 and as the latter rotates it operates the front end of said plunger in and out of the 15 opening 18. This plunger operates to prevent any hard or lumpy substance from remaining in or choking the conveyer as it rotates. The plunger 16 also acts as a cut-off to hold the coal against any backward 20 movement in the event the weight of the coal is greater in the fire box than in the hopper.

In the operation of my invention, the fuel is thrown into the hopper 7 and falls down into the conveyer and is carried into the fire 25 box and forced up under the fire and uniformly distributed along the entire length of the fire box. By feeding the fuel to the fire box from under the fire, all gases will be consumed and a more perfect combustion 30 produced, resulting in a great saving of fuel, and economy in operation.

Having thus described my invention, what I claim is:

1. In an underfeed furnace, the combination 35 with a fire-box, a concaved trough in said fire box, said trough tapering toward its rear end, a hopper connected with said trough, a hollow cone-shaped screw conveyer extending into said fire-box and having a 40 number of apertures therein leading into the fire-box, a gear-wheel on said conveyer, a power shaft having a worm thereon in mesh with said gear-wheel, a plunger having one end projecting into said hopper and adapted 45 to move between the flights of the conveyer whereby the fuel is held against any backward movement when the screw rotates, and

a link connecting said plunger with the said gear-wheel.

2. In an underfeed furnace, the combination 50 with a fire-box, a trough within said fire box, a hopper connected with the trough, a graduated screw conveyer extending from said hopper into the fire box, a gear wheel on the conveyer shaft, a driven shaft having 55 a worm thereon meshing with said gear wheel, a plunger having one end pivoted and its opposite end projecting into the hopper and adapted to move between the flights 60 of the conveyer whereby the fuel is held against any backward movement when the screw rotates, and a link connecting the said plunger with the gear wheel, whereby when the latter is rotated, the plunger will be operated in and out of said hopper. 65

3. In an underfeed furnace, the combination 70 with a fire box, a screw conveyer leading into said fire box, a gear-wheel on the conveyer shaft, a power shaft having a worm in mesh with said gear wheel, a 75 plunger having one end projecting into said conveyer and adapted to move between the flights of the conveyer whereby the fuel is held against any backward movement when the screw rotates, and a link connecting said plunger with said gear-wheel.

4. In an underfeed furnace, the combination 80 with a fire box, a hopper outside of said fire box, a screw conveyer leading from said hopper into said fire box, a gear-wheel 85 on the conveyer shaft, a power shaft having a worm in mesh with said gear wheel, a plunger having one end projecting into said hopper and adapted to move between the flights of the conveyer whereby the fuel is held against any backward movement when the screw rotates, and a link connecting said plunger with said gear wheel.

In testimony whereof I affix my signature in presence of two witnesses.

WILLIAM H. H. STINEMAN.

Witnesses:

CHAPIN A. FERGUSON,

ROBERT C. RHODES.
